UNITED STATES PATENT OFFICE.

JOHN B. McINTIRE, OF MITCHELL, INDIANA.

SUSPENSION-HOOK.

No. 908,602.

Specification of Letters Patent.

Patented Jan. 5, 1909.

Application filed January 21, 1908. Serial No. 411,904.

To all whom it may concern:

Be it known that I, JOHN B. McINTIRE, citizen of the United States, residing at Mitchell, in the county of Lawrence and 5 State of Indiana, have invented certain new and useful Improvements in Suspension-Hooks, of which the following is a specification.

The object of this invention is an improved device which is designed to be attached to tickets, books, papers or similar objects and to suspend the same in a substantially vertical position as may be desired for filing, displaying purposes or the like. And 10 a further object of the invention is a device of the character described which when employed in connection with a file, effects the greatest economy of space and permits the quick removal of any desired object suspended in the file, and which renders said objects readily accessible and easily and conveniently rearranged.

With these and other objects in view that will more fully appear as the description proceeds, the invention consists in certain constructions and arrangements of parts that I shall hereinafter fully describe and claim.

For a full understanding of the invention and the merits thereof, reference is to be had 30 to the following description and the accompanying drawing, in which:

Figure 1 is a perspective view of a case showing my improved suspension hooks applied thereto. Fig. 2 is a transverse section thereof. Fig. 3 is a perspective view, and, Fig. 4 is a detail view in horizontal section of the attaching member.

Corresponding and like parts are referred to in the following description and indicated 40 in all the views of the drawing by the same reference characters.

This improved device embodies a suspension hook 1, comprising a hook portion 2 and an attaching portion 3, and is preferably constructed of an integral strip of wire or the like doubled upon itself near one end, to form two substantially parallel spaced members 4 which constitute the attaching portion, the said extremity of the strip being curved laterally, as shown, and the strip extending 50 parallel thereto to form a winding passage at the upper end of the attaching portion. The strip thence curves upwardly beyond such end, as indicated at 5, to form the hook portion 2, the extremity 6 of which extends

downwardly, as shown, and terminates above and in vertical alinement with the attaching portion 3. This hook is designed to be secured to the object to be filed by means of a fastener 7 which passes through said object 60 near the upper end thereof and between the spaced members 4 of the attaching portion, the ends of such fastener being spread out laterally as shown to hold the fastener in position in the object and to secure the hook to 65 the latter. From this arrangement, it will be noted that the suspended object may be quickly detached from the hook, by pushing the fastener upwardly between the spaced members 4 of the attaching portion 3, the 70 winding passage at the upper end of the latter serving to effectually prevent accidental disengagement of the fastener from the hook.

In the practical use of my improved device, the hook portion 2 is inserted in an upwardly 75 facing groove formed in the filing case, as clearly shown in Fig. 1, with the extremity of said hook portion resting on the bottom of the groove and serving as a swivel by means of which the object may be freely turned as 80 desired. Since the extremity of the hook portion is in alinement with the attaching portion 3, the object will obviously be suspended in a substantially vertical position. The hooks may be quickly removed from the 85 groove to permit the rearrangement of the objects in the filing case, or the like, and may be slid longitudinally in the groove to vary the distance between the objects and render them easily accessible.

From the above description in connection with the accompanying drawing, it will be seen that I have provided a simple, durable and efficient construction of device of the character described which is most handy and 95 may be conveniently employed for various other purposes that will present themselves to the user.

Having thus described the invention, what I claim is:

1. A device of the character described, comprising a suspension hook constructed of an integral strip doubled upon itself intermediate of its ends to form spaced members constituting the attaching portion of the 105 hook, said strip being curved upwardly to form the hook portion, the extremity of which extends downwardly toward and terminates above and in alinement with the attaching portion, and a fastener passing be- 110

tween the spaced members of the attaching portion, and adapted to secure the same to the object to be suspended.

2. A device of the character described, comprising a suspension hook constructed of an integral strip doubled upon itself intermediate of its ends to form spaced members constituting the attaching portion of the hook, said strip being curved upwardly to 10 form the hook portion, the extremity of which extends downwardly toward and terminates above and in alinement with the attaching portion, and a fastener passing between the spaced members of the attaching portion, and adapted to secure the same to the object to be suspended.
- 15 3. A device of the character described, comprising a suspension hook constructed of

an integral strip doubled upon itself near one end, to form substantially parallel spaced members constituting the attaching portion of the hook, the said end being curved laterally and the strip coacting therewith, to 25 form a winding passage, said strip being then bent upwardly beyond such end to form the hook portion, the extremity of which extends downwardly toward and terminates above 30 and in alinement with the attaching portion, and a fastener passing between the spaced members of the attaching portion and adapted to secure the same to the object to be suspended.

In testimony whereof I affix my signature in presence of two witnesses.

JOHN B. McINTIRE. [L. S.]
